UNITED STATES PATENT OFFICE.

JOHN C. KOPF, OF BELLEVUE BOROUGH, PENNSYLVANIA, ASSIGNOR TO THE DUFF MANUFACTURING COMPANY, OF PITTSBURGH, PENNSYLVANIA, A CORPORATION OF PENNSYLVANIA.

JACK.

1,317,878.

Specification of Letters Patent.

Patented Oct. 7, 1919.

Application filed May 15, 1919. Serial No. 297,237.

To all whom it may concern:

Be it known that I, JOHN C. KOPF, a citizen of the United States, and resident of the borough of Bellevue, in the county of Allegheny and State of Pennsylvania, have invented a new and useful Jack, of which the following is a specification.

The invention relates to pushing and pulling devices, and particularly to jacks, and 10 specifically is an improvement upon that type of jack long known wherein a double rack-bar, that is to say one provided with rack teeth upon both sides, is rolled upward between a pair of simultaneously acting pinions, instead of being slid up by a single pinion and set of rack teeth against friction. The object is to provide a jack or 15 similar device combining the advantage of this principle of operation for moving heavy 20 loads, with a novel and improved self-locking driving means whereby high mechanical efficiency, great strength, and simplicity of manufacture are obtained. Worm gearings have been well known as self-locking power- 25 driving means for jacks, but the present jack-operating means differs essentially from a worm gearing, in acting radially instead of axially, in exhibiting line contact 30 instead of face contact, and in having a greater angle of efficiency and less friction.

A general object is to provide a simple, strong, compact, serviceable, and easily manufactured jack or the like.

In the accompanying drawings forming a 35 part hereof:

Figure 1 is a sectional side elevation of a jack embodying the invention;

Fig. 2 is an elevation at right angles to Fig. 1 looking into the screw box, the cover 40 of which has been removed, and showing the double spiral gear of the invention partly in section and partly in elevation, the jack handle being also shown partly in section and broken away;

Fig. 3 is a horizontal section in the plane of the rack-pinion and buttress gear shafts, 45 looking upward;

Fig. 4 is a vertical section in the plane of one of said shafts;

Fig. 5 is a fragmentary elevation showing the double rack, pinions and buttress-gears; 50 and

Fig. 6 is a view of the inner part of the jack-handle, mainly in section.

The jack shown in the drawings has a

frame or housing, in the form of an upright stand 1 with expanded base 2. Throughout the height of the housing is a rack-guide channel 3. In this guide is a rack 4, having rack-teeth 5 upon opposite 60 sides. The faces of the bar are channeled as seen in Fig. 3, the inner channel being designated 6.

At opposite sides of the rack-bar, in the upper back part of the stand are pinion 65 chambers 7, behind which are rear or outer bearing bosses 8 in the wall. At the opposite or forward part of the stand is a gear-box 9, having a cover 10, secured by screws 11. Horizontal tubular inner bearing bosses 12 are formed in the interior of the housing, in alignment with the outer bearings 8, the internal diameter of the bosses 12 however being greater. Bushings 13 are seated in the bosses 12, and pinion shafts 14 are 70 journaled in said bushings and in the rear bearings 8. Pinions 15 on the shafts between the journal portions 16 and 17 mesh with the teeth of the rack. In assembling, the shafts with the pinions thereon are inserted through the bosses 12 from the front of the gear-box, the interior of said bosses being made a little larger than the pinions to permit them to pass. Thereafter the bushings are introduced into their seats. 75 As shown in Fig. 5, the teeth of the pinions are bent forward, thus avoiding undercutting and securing a good rolling contact. 80

The forward portions of the shafts 14 are 85 made polygonal, and upon them within the gear-box are gears 18. These gears are made with straight buttress teeth, that is to say teeth having substantially perpendicular or radial working faces 19, extending in the transverse direction parallel with the axis, 90 and sloping backs 20, each tooth being thus approximately a right-angled triangle. An operating shaft 21 rests in channel bearings 22 in the bottom of the gear-box, formed part in the body and part in the cover; and 95 on this shaft, projecting between the converging arcs of the buttress gears 18, is a double conical buttress pinion 23. The buttress teeth 19 are reversed upon the two gears 18 and face toward the double pinion 23 between them. Each side of this pinion is formed with a spiral buttress working face 24, and by spiral I mean a thread which winds about the axis at increasing distance 100 therefrom, as distinguished from a helical 105

110

thread. This spiral working face is of a length to engage a series of teeth, in this instance three, at a time, and in order to follow the curve of the gear it possesses also 5 a lesser pitch in the longitudinal direction. The spiral pitch causes driving pressure perpendicular to the operating shaft 21, the helical pitch enabling the working face 24 to pursue the teeth of the gear as they travel 10 upward in their curved path, so that the driving pressure is constantly applied at a plurality of points. Both the predominating spiral and the attendant helical pitch are constantly varying, as is also the working 15 face angle, the variation being such as to enable the parts to mesh in the manner indicated. The contact between the working face of the pinion and the working face of each gear tooth in action is a single line, 20 thereby reducing friction. The triangular form of the teeth 19 of the oppositely rotatable gears gives strength to these parts; and in the driving pinion 23 the body itself 25 resists shear. An advantage of the construction is that the two sides of the double conical spiral buttress pinion can be cut at one operation, which is both economical and insures perfect synchronism, the latter being of primary importance in a jack of this type, 30 because if the two sides of the mechanism are not in harmony the work will fall mainly on one of them. On the other hand, in manufacturing the frame and working parts and assembling them, it is not necessary to 35 observe great accuracy as to centers, as the gearing will work efficiently with considerable variation in this respect, because of the line contact. The double pinion is preferably made as an integral member, but it 40 might manifestly be split or made in two halves secured to the operating shaft, though less desirably. In operation the periphery of the spiral pinion passes within the channel 6 of the rack-bar. 45 The top of the rack-bar bears a head 25, preferably formed of a separate piece having a hole, through which a stud projection 26 of the bar is passed and riveted over. From the head there depends rigidly a toe- 50 lift bar 27, having a slide block 28 formed on its lower portion to operate in an external channeled slideway constituted by bearing surfaces 29 upon the outer face of the wall and vertical ribs 30 projecting therefrom. The sides of the toe-lift bar are channeled as indicated at 31, and its outer edge is 55 provided with a series of customary holding notches 32. The adjustable toe-lift 33 is of known kind, having lugs 34 embracing the 60 channeled sides of the bar and a dog extremity 35 to engage the holding notches. Heretofore difficulty has been experienced from the toe-lift becoming dislodged. To overcome this means are hereby provided for 65 causing the toe-lift to seek the notches, such

means being preferably embodied as a counterweight 36 on the bracket web 37 adjoining the platform 38 and limb 39 of the toe-lift.

A rocker 40 is journaled on the projecting 70 end of the operating shaft 21, to which, between the cheeks of the rocker, is fixed a ratchet wheel 41 having symmetrical teeth. The rocker has a handle-socket 42 formed therewith as usual, to receive the handle 43. 75 A double reversible pawl 44 is pivoted at 45 between the sides of the rocker, at the base of the handle socket, where its back 46 can be encountered by an offset projection 47 on the end of the handle, so that according as 80 the handle is thrust into the socket with said projection at one side or the other of a pin 48 the pawl is shifted to one working position or the other. At one end, the pawl has two spring-seat notches 49, separated by a 85 protuberance 50, to receive the rounded end of a blade spring 51 in the respective positions of the pawl. A simple mode of mounting the spring, permitting of ready replacement, is secured by straining the spring beneath a bridge 52 on the handle socket, and by seating its rear end over a low stud 53, which passes through a hole in the spring. 90

In the lifting or working operation, the double spiral pinion 23 exerts lifting pressure 95 upon the teeth of the buttress gears 18, and the latter in turn cause the pinions 15 to lift the rack-bar 4 from opposite sides. Thus, the action as a whole is at right-angles to the operating shaft, and the reaction 100 is downward, being taken by the lower sides of the shaft bearings, with no tendency for endwise displacement.

What I claim as new is:

1. A jack, comprising a stand, a double 105 rack-bar therein bearing a head, and pinions meshing the rack-bar at opposite sides, and in combination therewith, a pair of buttress gears connected with the rack-pinions, a transverse operating shaft and a double 110 conical spiral buttress pinion on said shaft projecting in meshing engagement between said buttress gears and acting thereon at right angles to the operating shaft, the buttress gears having their teeth reversed and 115 facing toward the spiral pinion between them.

2. A jack, comprising a stand, a double 120 rack-bar therein bearing a head, and pinions meshing the rack-bar at opposite sides, and in combination therewith, a pair of buttress gears connected with the rack-pinions, a transverse shaft, a double spiral pinion on 125 said shaft meshing between said gears, the working faces of said spiral pinion having a helical pitch less than the spiral pitch and meshing with series of teeth on the converging arcs of the gears and acting thereon at right angles to the shaft, the buttress gears having their teeth reversed and fac- 130

ing toward the spiral pinion between them, and means for operating said pinion.

3. In a device of the character described, the combination with a frame, a double rack-bar movable relatively thereto, and pinions meshing the rack-bar at opposite sides journaled in the frame, of a pair of buttress gears connected with the rack-pinions, a transverse operating shaft and a double conical spiral pinion on said shaft projecting in meshing engagement between said buttress gears and acting thereon at right angles to the operating shaft, the buttress gears having their teeth reversed and 15 facing toward the spiral pinion between them.

4. A device of the character described, comprising a double rack-bar, pinions meshing therewith at opposite sides, shafts bearing said pinions, a housing chambered to accommodate the rack and pinions and having outer bearing for said shafts and inner bearings therefor of a size to permit the pinions to pass, bushings in said inner bearings, but-

tress gears on said shafts in front of the 25 bushings, a transverse operating shaft and a double conical spiral buttress pinion on said shaft meshing between said buttress gears and acting thereon at right angles to the operating shaft, the buttress gears having 30 their teeth reversed and facing toward the spiral pinion between them.

5. In a device of the character described, the combination of a frame, a rack-bar movable relatively thereto having rack-teeth 35 upon opposite sides and a channel in its face, pinions meshing the teeth upon opposite sides of the bar, buttress gears connected with the rack-pinions, a transverse operating shaft and a double conical spiral buttress 40 pinion projecting in meshing engagement between the buttress gears and positioned to project laterally into the channel of the rack-bar, said pinion acting upon the buttress gears at right angles to the operating 45 shaft, the teeth on the gears being reversed and facing the spiral pinion between them.

JOHN C. KOPF.
